DRIPLESS PITCHER

Thomas Bronston House, Danville, Ky., assignor
of one-half to Hazel House Prall, Danville, Ky.

Application June 13, 1952, Serial No. 20,181

Term of patent 14 years

(Cl. D44—21)

To all whom it may concern:

Be it known that I, Thomas Bronston House, a citizen of the United States, residing at Danville, in the county of Boyle and State of Kentucky, have invented a new, original, and ornamental Design for Dripless Pitcher, of which the following is a specification, reference being had to the accompanying drawing, forming a part thereof, and in which

Fig. 1 is a perspective view of a pitcher showing my new design;

Fig. 2 is a side elevational view; and

Fig. 3 is a top plan view thereof.

I claim:

The ornamental design for a dripless pitcher, substantially as shown.

THOMAS BRONSTON HOUSE,
